UNITED STATES PATENT OFFICE.

CHARLES H. LAMSON, OF PORTLAND, MAINE.

DESIGN FOR A BADGE.

SPECIFICATION forming part of Design No. 12,466, dated September 13, 1881.

Application filed May 9, 1881. Term of patent 7 years.

To all whom it may concern:

Be it known that I, CHARLES H. LAMSON, a citizen of the United States, residing at Portland, in the county of Cumberland and State of Maine, have invented and produced a new and original Design for Buttons, or for a Badge, or similar ornamental article, of which the following is a specification, reference being had to the accompanying drawings, forming a part 10 thereof, in which—

Figure 1 is a plan of my newly-designed article. Fig. 2 is an elevation of the same. Fig. 3 is a sectional view of the same on the line of its diameter.

15 The object of my design is twofold: first, to produce an ornamental device to be worn as a button or a badge, or in any similar manner; and, secondly, to provide an emblematic or distinctive badge for the riders and patrons of 20 bicycles and tricycles, known as "wheelmen."

The principal feature of my design is the representation of a wheel, with its rim, spokes, and hub, with wings attached to the latter, thus making it emblematic of the swiftly-flying wheel.

25 Various forms of construction of this design, of course, may be used, and among others I mention that consisting in making a circular disk with the rim, hub, spokes, wings, and 30 groundwork between them of different materials, or different colors, or both; also, that consisting in striking up the disk so as to make its general contour not only circular but convex in its face, and having the wings and other 35 parts of the design in relief or cameo.

This design may be used either with or without indicating letters or a monogram. Thus the letters "L. A. W." in the design shown in Fig. 40 1 mean "League of American Wheelmen;" or, instead of the letters "L. A. W.," others may be used—as, for instance, "B. Bi. C.," for "Boston Bicycle Club," in this manner making the button or badge emblematic, not only of the general idea of wheelmanship, but of the specific idea of membership in the wheel-club.

The face of this design is circular in contour, the outside being like the rim of a wheel, and at the center is a small circular part, like the end of a hub, from which lines or ribs or grooves radiate like spokes. Over these, and 50 radiating at equal distances apart toward the rim, are three wings, as shown. The whole may be either flat or convex, (like the side of a suspension-wheel,) plain or engraved, or raised and depressed in surface, or of the same or 55 different materials, as may be desired. On the under side I attach a stud for holding the same in a button-hole; or a pin may be attached, and it may be made of any desired size. The ground may be of silver or nickel, with 60 the spokes in enamel, and the wings, hub, and rim may be in gold or gilt, and the hub and rim may be in red gold and the wings in yellow gold. It may be used for a button, pin, badge, or locket-side, &c. In the center of the 65 hub may be a small diamond, ruby, or other stone.

I claim—

1. A design for a badge, consisting of a circular rim, a hub in the center, spokes radiating from the latter to the frame, and wings thereon.

2. A design for a badge, consisting of a circular rim, a hub in the center, spokes radiating from the latter to the former, and wings 75 thereon, these parts being formed on a convex surface, as shown and described.

3. A design for a badge, consisting of a circular rim, a hub in the center, spokes radiating from the latter to the former, and wings 80 thereon, and alphabetical letters between the wings, formed within the rim, as shown and described.

CHARLES H. LAMSON.
